(57) **CLAIM**

The ornamental design for fart noise device, as shown and described.

DESCRIPTION

FIG. 1 is a front perspective view of a fart noise device in accordance with the new design;

FIG. 2 is a bottom perspective view thereof;

FIG. 3 is a side view thereof;

FIG. 4 is a top view thereof; and,

FIG. 5 is a bottom view thereof.

The broken lines shown in the figures depict portions of the fart noise device that form no part of the claimed design.
